LOCK TOP METAL CONTAINER

Charles Schmidt, Passaic, N. J., assignor to Continental Can Company, Inc., New York, N. Y., a corporation of New York

Application October 31, 1935, Serial No. 47,691

3 Claims. (Cl. 220—40)

The present invention relates to new and useful improvements in metal containers and more particularly to a metal container wherein the cover may be quickly attached and positively held in locked engagement with the container body.

The present invention particularly relates to an improvement in a container of the type shown in the copending application of Charles Schmidt, Serial No. 27,971, filed June 22, 1935. In the use of containers of the type shown in the above application, it has been found that when the cover is snapped over the container end with the cooperating locking devices on the container body and on the cover in alignment, the metal on the cover between adjacent holding lugs will spring inwardly and sometimes bite into the body portion of the container, thus disfiguring the cover and preventing a proper seating of the cover on the container body. It has also been found that when the cover is placed on the container body and given a slight turning movement to lock the same together, the holding lug on the cover will sometimes pass over the stop shoulder on the container body because of the straightening out of the metal on the cover flange between adjacent holding lugs thereon. Then, too, when the metal of the cover flange is bent out of line before the cover is applied to the container body, some of the holding lugs will be only loosely engaged because of this tendency of the metal on the cover flange to straighten out between the holding lugs. The present invention aims to overcome the above and other difficulties.

An object of the invention is to provide a metal container wherein the cover and the container body are provided with cooperating locking parts and wherein means are provided for maintaining the shape of the cover flange when it is pressed on and locked to the container body so as to insure a positive locking engagement therebetween.

The above and other objects of the invention will in part be obvious and will be hereinafter more fully disclosed.

In the drawing:

Fig. 1 is a fragmentary side elevation showing a container and a cover therefor with the parts separated.

Fig. 2 is a diagrammatic view showing the position of the detents on the cover flange and the holding lugs on the container body without the improvement of the present invention.

Fig. 3 is a similar diagrammatic view embodying the improvement of the present invention.

Fig. 4 is a diagrammatic view showing the position of the cover and container according to the present invention with the same in locked engagement.

Fig. 5 is a diagrammatic view showing the stop shoulders on the container and the holding lugs on the cover in the position which sometimes occurs without employing the present invention.

Fig. 6 is a similar diagrammatic view showing the cooperating parts on the container embodying the improvement of the present invention.

Fig. 7 is a fragmentary side view in section showing the cover and container body in closed position embodying the improvement of the present invention.

Fig. 8 is a similar side view in section showing the locking parts.

Referring more in detail to the accompanying drawing, the container includes a body portion 10 curled inwardly at the open end thereof to provide a closed strengthening bead indicated at 11. At a short distance beneath the beaded edge 11, the body is curled outwardly to form a strengthening bead as indicated at 12. Between the beads 11 and 12 at spaced intervals are locking lugs which are all similar in construction so that the description of one will answer for the others. These locking lugs are formed by bending the metal of the body portion outwardly and are indicated at 13. Each locking lug 13 is shaped to provide an upper edge portion 14 which is substantially parallel with the upper beaded edge 11 of the container body. The lower edge portion 15 of the locking lug is inclined downwardly from right to left as viewed from the outside of the container. This inclined edge portion 15 terminates in a depending vertically disposed stop shoulder 16 which merges into the upper edge of the bead 12. The bead 12 thus serves to aid in preventing the body portion in the region of the stop shoulder 16 from springing to allow the lug on the cover to slip by. Portions of the locking lug 13 are forced inwardly to provide spaced depressions or recesses 17, 18. In the space between adjacent locking lugs 13 on the container body, the metal of the container is bent outwardly to form lugs 19 which extend outwardly from the container body substantially the same distance as the locking lugs 13. These lugs or projections 19 are disposed slightly above the bead 12.

The cover, which is indicated at 20 in the drawing, has a depending flange 21 which is curled outwardly to form a solid bead 22 so as to strengthen the lower edge thereof. Directly

above the beaded lower edge of the cover flange 21 are a series of holding lugs 23 which are symmetrically spaced with respect to the locking lugs 13 on the container body. These lugs 23 extend inwardly from the cover flange 21 and are parallel with the beaded edge 22 and, while disposed directly above the beaded edge, they do, in effect, merge into the beaded edge so that they will not spring except as the edge springs. The holding lugs 23 are relatively short and dimensioned so that they will pass through the space between the locking lugs 13 on the container body, and when the cover is turned, the lugs 23 will pass beneath the inclined face 15 of the lugs 13 so as to draw the cover down into tight sealing contact with the container body.

As shown in the foregoing copending application, the cover is provided with a peripheral depression which forms the U-shaped channel 24 which contacts with the upper curved face of the bead 11 so as to form a tight sealing contact therebetween when the cover is drawn down onto the container body. The inclined face 15 of the locking lug 13 is so dimensioned that the lug 23 on the cover comes into contact with the vertical stop shoulder 16 when the cover is in tight sealing contact with the container body. An additional sealing contact is also made between the bead 22 on the cover and the strengthening bead 12 on the body. The cover is provided with a knurled portion 25 by which the cover may be easily turned.

Directly above the lug 23 on the cover is an inward projection or detent 26. As the lug 23 passes along the inclined face 15 on the lug 13, the detent 26 will pass up onto the face of the lug 13 and into the recesses 18 and 17 in order, thus providing a positive locking means for preventing any accidental turning of the cover relative to the container body.

Referring to Figs. 2, 3 and 4 of the drawing, and particularly at this time to Fig. 2, there is shown diagrammatically what often occurs in the use of lock-top containers of this type where in no means are provided for preventing the straightening of the cover between adjacent lugs thereon. There is a decided tendency for the metal of the depending flange 21 on the cover to straighten out and tend to assume a straight line position between adjacent detents 26 as the said detents pass over the raised portions of the locking lug 13 on the container body. As the flange on the cover approaches the body portion of the container, there is less resistance offered to the passage of the detents 26 out of the recesses in the locking lugs 13 on the container body so that it often occurs that the detents 26 will pass out of the recesses 17, thus rendering this locking means ineffectual for preventing accidental turning of the cover. This is illustrated particularly in Fig. 2. In Fig. 3, however, the present invention is illustrated diagrammatically showing the lug 19 which tends to prevent the straightening out of the cover flange between adjacent holding lugs thereon. Since the metal of the cover flange is limited in its movement toward the body portion of the container and thus prevented from straightening out to the extent illustrated in Fig. 2, there is an increased resistance offered to the passage of the detents 26 over the raised portions of the locking lugs 13 so that any tendency for the detents 26 to pass out of the recess 17 in the lug 13 is prevented. The parts are shown in locked position in Fig. 4 and it will be seen that the container

body and the cover flange are maintained in substantially parallel relationship entirely around the same. The lugs 19, by holding the cover flange 21 away from the body portion of the container, tend to urge the detents 26 into the recesses in the locking lugs 13.

Referring to Fig. 5, there is illustrated diagrammatically a similar tendency for the holding lugs 23 on the cover flange to pass over the stop shoulder 16 on the locking lugs 13 when the metal of the cover flange 21 between adjacent holding lugs straightens out and approaches the body portion of the container. Thus, it sometimes occurs that the holding lugs 23 on the cover will pass over the stop shoulders 16 as often occurs with the detents 26, as indicated above. However, the provision of the lugs 19 to limit the inward movement of the cover flange 21 will prevent the inward flexing of the cover flange, thus effectually preventing any tendency for the lugs 23 to pass over the stop shoulders 16.

In forming the lugs on the cover flange, there is a tendency to produce a non-cylindrical cover flange. In other words, the flange between adjacent holding lugs tends to straighten out and assume a hexagonal shape when, as illustrated in the accompanying drawing, six holding lugs are employed. In the placing of the cover on the container, very often the holding lugs 23 on the cover flange are placed directly over the locking lugs 13 on the container body, as shown in Fig. 1, and the cover is pressed down, causing the holding lugs to snap over the locking lugs and effect a locking engagement in this manner. This outward pressure on the holding lugs of the cover flange, together with the tendency of the flange to straighten out, sometimes causes the lower edge of the flange to bite into and grip the wall of the container body to such an extent that the seating of the cover is prevented and there results a disfiguration of the container. The locking lugs 19 prevent this occurrence for the reason that these lugs contact with the lower edge of the cover flange between the holding lugs 23 thereon and prevent its inward flexing. In this manner, the cover flange, under the conditions stated, is positively held from biting into and destroying the container body.

It is to be clearly understood that minor changes in the details of construction and the arrangement of parts may be made without departing from the scope of the invention as set forth in the appended claims.

I claim:

1. A metal container comprising an open-ended body portion, said body portion being shaped below and adjacent the open end thereof to form a series of spaced locking lugs, each of said lugs having a downwardly inclined lower face terminating in a vertical stop shoulder, and a cover having a depending flange, said flange being shaped to provide a series of relatively short holding lugs cooperating with the inclined faces of the locking lugs on said body portion for locking the cover thereon, and said body portion being provided with lugs located between adjacent locking lugs thereon and extending substantially the same distance away from the body portion for preventing the inward flexing of the cover flange between adjacent holding lugs thereon and thereby preventing the outward flexing of the cover flange in the region of the holding lugs thereon so as to prevent the said holding lugs from slipping over said shoulders when the cover is finally seated.

2. A metal container comprising an open-ended body portion, said body portion being shaped below and adjacent the open end thereof to form a series of widely spaced locking lugs, a cover 5 having a depending flange, said flange having a series of widely spaced holding lugs cooperating with the locking lugs on said body portion for locking the cover thereon, and means disposed on said body portion between adjacent locking 10 lugs for maintaining the cover flange substantially parallel to the body portion during the seating of the cover thereon.

3. A metal container comprising an open-ended body portion, said body portion being shaped below and adjacent the open end thereof to form a series of widely spaced locking lugs, 15

each of said locking lugs having a downwardly inclined lower face terminating in a vertical stop shoulder, a cover having a depending flange, said flange being shaped to provide a series of relatively short widely spaced holding lugs cooperating with the inclined faces of said locking lugs on the body portion for locking the cover thereon, and means disposed between said cover flange and the body portion of the container and intermediate adjacent lugs for preventing the inward flexing of the cover flange between adjacent lugs thereon whereby to prevent said lugs from slipping over said shoulders when the cover is finally seated.

CHARLES SCHMIDT. 15
